DESIGN FOR A DISPENSING DEVICE

Wilbur Henry Adams, Cleveland, Ohio, assignor
to Erie Meter Systems, Inc., Erie, Pa., a corporation of Pennsylvania

Application October 1, 1936, Serial No. 65,100

Term of patent 7 years

To all whom it may concern:

Be it known that I, Wilbur H. Adams, a citizen of the United States, residing at Cleveland, in the county of Cuyahoga and State of Ohio, have invented a new, original, and ornamental Design for a Dispensing Device, of which the following is a specification, reference being had to the accompanying drawing, forming a part thereof, wherein:—

Fig. 1 is a side elevation of the dispensing device showing my new design.

Fig. 2 is a front elevation of said device.

I claim:

The ornamental design for a dispensing device
as shown.

WILBUR HENRY ADAMS.
